UNITED STATES PATENT OFFICE

STEPHEN FAITH, OF CHICAGO, ILLINOIS

DESIGN FOR A VEHICLE ORNAMENT

Application filed September 15, 1932. Serial No. 44,840. Term of patent 14 years.

To all whom it may concern:

Be it known that I, STEPHEN FAITH, a citizen of the United States, residing at Chicago, in the county of Cook and State of Illinois, have invented a new, original, and ornamental Design for a Vehicle Ornament, of which the following is a specification, reference being had to the accompanying drawing, forming part thereof.

Fig. 1 is a side elevational view of a vehicle ornament embodying my new design; and

Fig. 2 is a front elevational view thereof.

I claim:

The ornamental design for a vehicle ornament as shown.

In witness whereof, I hereunto subscribe my name this 9 day of September, 1932.

STEPHEN FAITH.
